US00D590232S

(12) **United States Design Patent**
Demers et al.

(10) **Patent No.:** US D590,232 S
(45) **Date of Patent:** ** Apr. 14, 2009

(54) **TOOL KNOB**

(75) Inventors: **Brian Joseph Demers**, Huntersville, NC (US); **Joseph Allen Berlepsch**, Mooresville, NC (US)

EM 000702089-0002 6/2007
JP D1253453 10/2005

(73) Assignee: **Lowe's Companies, Inc.**, Mooresville, NC (US)

(**) Term: **14 Years**

(21) Appl. No.: **29/249,386**

(22) Filed: **Oct. 4, 2006**

(51) **LOC (9) Cl.** 08-05

(52) **U.S. Cl.** D8/107

(58) **Field of Classification Search** D7/395; D32/49; D8/20, 21, 51, 52, 58, 61, 68, 75, D8/80, 82, 83, 90, 94, 95, 97, 107, 300, 303; 81/177.1, 489, 52; 16/422; D4/138

See application file for complete search history.

(57) **CLAIM**

The ornamental design for a tool knob, as shown and described.

DESCRIPTION

FIG. 1 is a perspective view of the tool knob of the present invention;

FIG. 2 is an elevational view of the right side of the tool knob of FIG. 1;

FIG. 3 is an elevational view of the front side of the tool knob of FIG. 1;

FIG. 4 is an elevational view of the left side of the tool knob of FIG. 1;

FIG. 5 is an elevational view of the rear side of the tool knob of FIG. 1;

FIG. 6 is a plan view of the bottom side of the tool knob of FIG. 1; and,

FIG. 7 is a plan view of the top side of the tool knob of FIG. 1.

The broken lines shown herein are for illustrative purposes only and form no part of the claimed design.

1 Claim, 7 Drawing Sheets
